UNITED STATES PATENT OFFICE.

ARTHUR L. SYMMONDS AND MARLIN T. SYMMONDS, OF COLORADO SPRINGS, COLORADO.

BRICK-MACHINE.

SPECIFICATION forming part of Letters Patent No. 727,489, dated May 5, 1903.

Application filed December 29, 1902. Serial No. 137,081. (No model.)

To all whom it may concern:

Be it known that we, ARTHUR L. SYMMONDS and MARLIN T. SYMMONDS, residing in the city of Colorado Springs, county of El Paso, and State of Colorado, have invented certain Improvements in Brick-Machines, of which the following is a specification.

This improvement relates to pressed-brick machines in which the clay is received in a slightly-moist condition, placed in molds, and subjected to a very heavy pressure. When the brick is properly molded and pressed, it is raised from the mold and pushed forward through the gate onto a table by means of a plunger. From there it is loaded on a truck or wheelbarrow and taken away for further treatment. Heretofore these machines have proved faulty, because they allowed a rough feather-edge to remain on the brick after it had passed through the gate. When the brick were loaded on a truck for removal, this edge would be detached by its coming in contact with other brick and the grit and waste allowed to drop on and get between other brick and damage their smooth surface.

The object of this improvement is to overcome that fault and remove the feather-edge and roughness before the brick leave the machine.

This improvement consists of the parts hereinafter set forth and described and may be attached to any dry-press brick-machine.

We attain the objects of our invention by means of the mechanism illustrated in the accompanying drawings, in which—

Figure 1 represents a front view of an ordinary dry-press brick-machine with our device attached. Fig. 2 shows arms used in attaching our device to such machine. Fig. 3 shows a front view of one of the bars which support our brush or scraper. Fig. 4 shows a rear view of the same bar, and Fig. 5 a side view of the same bar. Fig. 6 represents the metallic brush or scraper.

Like parts are referred to in all the figures by the same letters of reference.

Referring to the details of the drawings, the letters A A represent the sides of the frame of a brick-machine.

B B B B represent the table projecting in front of such machine.

C C represent the right and left arms, which when attached to the frame form a support from which the scraper D is suspended.

D represents the scraper-bar.

E E E E represent the brick as they are being pushed out onto the table B B B B.

a a a a represent the metallic blades, each of which are attached to the bar D by means of the hinges b b and b'.

d represents a flat steel spring, which is attached at one end to the bar D by screws or rivets, as shown, the other bearing on the blades a a a a and causing the blades a to press on the surface of the brick as they pass under, yet allowing enough movement to allow for slight variations in the thickness of the brick.

g g represent hinges on the bars F. (More particularly shown in Figs. 3 and 5.) The bar F is thus hinged to permit its being swung upward when the key o is raised above the staple r, as shown in Fig. 5. This allows the scraper to be displaced for the purpose of cleaning the dies and table. The arms C C are attached to the frame of the machine by means of screws or bolts passing through the open slots m' in the ends of the arms C C. To the other ends of the arms C C are attached bars by means of the bolts h, passing through the slots n and n' in the arms and k' k' in the bars, to which the scraper and parts necessary thereto are attached.

The elongated slots n n' and k' k' will permit of the adjustment of the height of the scraper for different machines and different thicknesses of brick. The elongated slots k' k' will also allow the bar to be raised or lowered and may have a scale on it, so that the changes may be more readily made.

The method of operation of our improvement is briefly described as follows: When the brick E E E E are pushed upward from the molds and then forward on the table B B B B, they are pushed under the blades a a a a of the scraper. As they pass under these blades the blades bear firmly on their surface, and any imperfection or feather-edge is scraped or brushed off, and the bricks leave the table clean, smooth, and perfect. When it is desired to clean the dies or table, the keys o o are raised and the scraper swung for

ward and upward out of the way on the hinges *g g*. When it is found that the scraper is not bearing evenly, is too high or low, because of wear or change in the size of the 5 brick, it may be adjusted by means of the bolts *i i* in the slots *k k*, or if a greater adjustment is to be made then by loosening the bolt *h* and permitting the bars *F F* to be shifted.

10 Having thus described our invention, we claim as new and desire to secure by Letters Patent—

15 1. In a pressed-brick machine the combination with the gate and table, of a metallic spring scraper or brush attached thereto by means of arms and hinged bars, having slots

and bolts allowing ready adjustment, substantially as described and for the purposes set forth.

2. In a pressed-brick machine the combination with the gate and table of an adjustable metallic spring-scraper supported by hinged bars substantially as shown and for the purposes set forth.

In testimony whereof we have signed our 25 names to this specification in the presence of two subscribing witnesses.

ARTHUR L. SYMONDS.
MARLIN T. SYMONDS.
